UNITED STATES PATENT OFFICE.

WILTSIE F. WOLFE, OF NEW YORK, N. Y., ASSIGNOR, BY MESNE ASSIGNMENTS, TO THE SMOKELESS COMBUSTION COMPANY, A CORPORATION OF WEST VIRGINIA.

DOWNDRAFT-STOVE.

SPECIFICATION forming part of Letters Patent No. 729,028, dated May 26, 1903.

Application filed August 25, 1899. Serial No. 728,435. (No model.)

To all whom it may concern:

Be it known that I, WILTSIE F. WOLFE, a citizen of the United States of America, residing at New York, in the county of New York and State of New York, have invented certain new and useful Improvements in Downdraft-Stoves, of which the following is a specification.

My invention has reference to improvements in downdraft stoves or furnaces—that is to say, to those in which the air necessary for the combustion of the fuel or the maintenance of the fire is conducted from above the fuel and the products of combustion are carried away from below.

My invention has for its object to improve and simplify the construction of stoves or furnaces adapted for the consumption of bituminous or soft coals; and to this end it consists, essentially, in the combination, in a downdraft-stove, of a fire-box or magazine, a fuel-support at the bottom of the fire-box or magazine, and an air-directing plate, guard, or skirt extending around or partially around the said fire-box or magazine and adjacent to the wall or walls of the same, all constructed for the purpose of conducting the air and the products of combustion downwardly through the fuel under the influence of the draft in a solid sheet.

The nature of my invention will best be understood when described in connection with the accompanying drawings, in which—

Figure 1 represents a vertical section of a cooking-stove embodying my invention, part being broken away. Fig. 2 is a plan or top view of the same. Fig. 3 is a section on the line 3 3, Fig. 1. Fig. 4 is a vertical section similar to Fig. 1, but drawn on an enlarged scale. Fig. 5 is a perspective view of the air-directing plate, drawn on the same scale as Fig. 4. Fig. 6 is a vertical section similar to Fig. 1, but illustrating a modified manner of introducing the air into the fire-box or magazine. Fig. 7 is a plan or top view of the construction shown in Fig. 6. Fig. 8 is a vertical section of a heating-stove provided with my improvements. Fig. 9 is a horizontal section on the line 9 9, Fig. 8. Fig. 10 is a plan or top view of the construction shown in Fig. 8.

Similar letters and numerals of reference designate corresponding parts throughout the several views of the drawings.

Referring at present to Figs. 1, 2, 3, and 4 of the drawings, the letter A designates a stove or range adapted for cooking purposes and for heating water, the same being in general of any approved form or construction. The stove, as usual, is provided with a fire-box or magazine 9, preferably located at or near its front, which is closed at its bottom by a suitable fuel-support 10, preferably made imperforate and adapted to be rocked, dumped, or shaken to remove the ashes or other solid products of combustion to the ash-pit 11. In the fire-box or magazine and near the rear of the same is placed a bridge-wall 6, which terminates at some distance above the top of the fuel-support, said bridge-wall being secured in the stove at its opposite ends 70 and held from above by means of a hanger 7, bolted or otherwise secured to the top plate 12 of the stove. To the top plate 12 of the stove is secured a downwardly-extending air-directing plate 4, which extends along the front wall of the fire-box or magazine and also along the side walls of the same, it being arranged adjacent to said walls to leave a space 3 between said plate and the walls, so as to permit the passage of air under the influence 80 of the chimney-draft to the fuel from above in a line following the walls or part of the walls of the fire-box or magazine. The space between the walls of the furnace and the air-directing plate may be preserved by means 85 of suitable lugs 5, adapted to bear against the walls of the furnace. The air necessary for combustion is supplied to the passage 3 through openings 2, formed, preferably, at the front of the stove, and the quantity of this air may be regulated by a suitable gate 1 in a usual manner. Between said supply-passage for air and the openings 2 I prefer to form an air-chamber 13, so as to equalize the supply of air throughout the passage.

The air entering between the air-directing plate and the walls of the furnace under the action of the chimney or other draft passes downwardly through the fuel along said walls, and the combustion of fuel gradually 100

rises vertically along the path of the downward current of air, with the result that a vertical channel is formed in the coal along the line of air-supply. The coal adjacent to this channel naturally falls into such channel, and consequently the coal in the fire-box or magazine is continuously fed toward such channel, and therefore the body of the fuel is being continually broken up or agitated and caking or packing is positively prevented.

In the construction shown in Figs. 1, 2, 3, and 4 I have shown the air supplied to the passage 3 from the front of the stove—that is to say, horizontally; but of course it is understood that the air can be supplied from above. This latter construction I have shown in Figs. 6 and 7.

In Figs. 8, 9, and 10 I have shown a method of applying the air-directing plate to ordinary heating-stoves of circular design. Referring to said figures, the air-directing plate 4 is shown to be cylindrical in form with a conical top and secured to the top plate 12, or it may form a part of the latter. The top of the stove is closed by a cover 14, which can be removed for the introduction of fuel. The air-directing plate is of such diameter as to approach closely to the walls of the fire-box or magazine 9, and air is admitted to the intervening space 3 through openings 2, controlled by a suitable gate 1, as before described. The equalizing-chamber 13 is formed by the conical portion of the air-directing plate. At the bottom of the fire-box or magazine are formed lateral openings 15 for the passage of the products of combustion from the fire-box or magazine upwardly to the flue 16, leading to the chimney. The bottom of the fire-box or magazine is closed by a fuel-support 10 of any suitable construction, preferably an imperforate support.

It is evident that the air-directing plate need not necessarily extend entirely around the fire-box or magazine, as shown in Figs. 8, 9, and 10.

While I have herein shown the air-directing plate in circular and trough-shaped forms with flat surface, it is of course to be understood that the plate may be made with a corrugated surface or surfaces or in other form.

The equalizing-chamber 13, above referred to, serves to effect an even distribution of the

air above and throughout the extent of the opening or passage through which the air is directed upon the fuel, so that the air is directed downward upon the fuel evenly and tends to effect uniform combustion at all points along said inlet. 55

What I claim as new is—

1. In a downdraft stove or heater, the combination with a fire-box having a lateral outlet for gases at or near the level of the fuel-support, of a directing plate or guard extending downward within said fire-box at a short distance from and standing substantially parallel with the outer wall thereof, and serving to produce between itself and said wall an extended flue or passage for directing the supply of air downward upon and into the fuel in a thin sheet or stratum. 60

15 2. In combination with the fire-box of a stove or heater, having a lateral outlet for gases at or near the level of the fuel-support, a directing plate or guard extending downward within the fire-box in proximity to and continuing substantially parallel with an outer wall thereof, and terminating at or above the fire-level, substantially as described, whereby there is formed a flue or passage to direct a stratum of air downward upon and 75 into the fuel and in contact with the wall of the fire-box, along a considerable portion of the horizontal extent of said wall. 80

3. In combination with the fire-box of a stove or heater having a lateral passage or 85 outlet for the gases at or near the level of the fuel-support, a directing plate or guard extending downward within the fire-box in proximity to an outer wall thereof and terminating at or above the fire-level, substantially 90 as described, the space between the fire-box wall and the skirt or guard being of greater capacity in its upper than in its lower portion, whereby an equalizing air-chamber is produced; and a gate or damper opening into 95 said air-space and serving to control the ingress of air thereto, substantially as described.

In testimony whereof I have hereunto set my hand in the presence of two subscribing witnesses.

WILTSIE F. WOLFE.
